UNITED STATES PATENT OFFICE

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE

DRIVING-ROD CONNECTION FOR LOOM LET-OFF MECHANISM

Application filed November 11, 1929. Serial No. 406,188.

This invention relates to a let-off mechanism for looms and particularly to the actuating mechanism therefor.

A let-off mechanism has for its purpose the control of the rotation of the warp beam in the loom so as to let off under even tension the warps from the beam during, and as required by, the weaving operation. The controlling mechanism is usually operated by connection to the lay rocker shaft so that during each cycle of movement of the lay a predetermined amount of the warps is let off.

In a familiar type of let-off mechanism, a rocker arm is secured to the lay rocker shaft and connected by a driving rod to a pawl carrying lever which controls the operation of the let-off mechanism. A lost motion connection is necessary between the rocker arm and the driving rod. The usual connection at this point consists of a stud cast on the rocker arm and a longitudinally slotted casting on the driving rod cooperating therewith. As these parts are seldom, if ever, lubricated and are not carefully finished, a great deal of wear takes place between the casting and the stud, interfering with the proper operation of the mechanism and necessitating frequent replacement of the main portion of the rocker arm, of the casting on the driving rod, or both.

The object of the present invention is to provide a novel form of connection between the rocker arm and driving rod which will operate for long periods of time without substantial wear, without necessity of replacement of parts, and without requiring lubrication.

The nature and objects of the invention will appear more fully from the accompanying description and drawings and will be particularly pointed out in the claims.

As the invention relates to but one feature of construction in the let-off mechanism, and as the construction and operation of the let-off mechanism itself are well known and familiar to those skilled in the art, it is only necessary here to illustrate and describe those parts of a familiar type of let-off mechanism with which the invention is particularly con-

cerned in order fully to disclose a simple and preferred embodiment of the invention.

In the drawings:

Fig. 1 is a side elevation of a portion of a loom with only those parts shown with which the invention is particularly concerned. 55

Fig. 2 is an enlarged view of a portion of the construction shown in Fig. 1.

Fig. 3 is a right-hand end elevation of the construction shown in Fig. 2. 60

Fig. 4 is a detail of the construction.

A portion of the loom side frame 1 is shown in which is mounted the usual lay rocker shaft 2 which carries the lay swords and lay, not shown. A portion 3 of a ratchet wheel such as employed in a familiar type of let-off mechanism is illustrated and a pawl 4 for operating the ratchet wheel. This pawl is pivotally mounted on a pawl carrying lever 5 fulcrumed at 6. The driving rod 7 is pivoted at its rear end 8 to the pawl carrying lever 5 as usual. In the operation of the let-off mechanism, the driving rod moves endwise. When it is moved to the right, viewing Fig. 1, it actuates the pawl carrying lever 5 to cause the pawl 4 to advance the ratchet wheel 3. The rearward movement of the pawl is always the same, but its return or forward movement is to an indefinite point, depending upon the amount of let-off that is to take place under the control of the let-off mechanism. It is for this reason that there must be a lost motion connection between the rocker arm, which is for actuating the driving rod, and the driving rod. 75 20 25

In the construction illustrated, a two-part rocker arm is secured to the lay rocker shaft 2. The lower part 9 has a telescoping connection with the upper part 10 and these parts are adjustably secured together by the bolt 11. The forward end of the driving rod 7 is formed by a casting 12 secured by a set screw 13 to the rod proper. This casting extends alongside the upper end of the part 10 of the rocker arm and is provided with an integral boss 14 extending opposite the front face of the rocker arm. The part 10 of the rocker arm is also provided with integral symmetrical hub portions 15 on opposite sides of and at a point below its upper end. An 100 90 95

offset link 16 having a pair of pivot studs 17 and 18 connects the driving rod to the rocker arm, the stud 17 passing through a bearing in the end 12 of the driving rod, and through and concentric with the boss 14, and the pin 18 passing through a bearing in the hub 15 and rocker arm. This link is detachably secured in place and locked in position as by means of a washer and a cotter pin 19 passed through the pivot stud 18. The cotter pin 19 thus serves to hold together all three parts of the device. It will thus be seen that the link not only pivotally connects the driving rod to the rocker arm but supports the driving rod. The face 20 of the boss 14 engaging the face of the rocker arm is curved, as shown in Fig. 4, so as to maintain constant the distance from the pivotal axis of the link and driving rod as the rocker arm swings with the boss in engagement with the driving rod.

An important feature of the above described construction is the symmetrical design and arrangement of the parts which enables them to be assembled on either the right or left hand side of the rocker arm thus adapting the device to a right or left hand loom. It will be apparent from the drawings that the device may be disassembled by removing the cotter pin 19 which permits the three major parts of the device to be separated one from the other. The link 16 may be reinserted in the rocker arm from the opposite side while the casting 12 on the end of the driving rod when reassembled on the stud 17 of the link member will be on the opposite side of the rocker arm. Due to the symmetrical shape of the parts the boss 14 on the casing 12 is positioned in the proper plane to be engaged by the rocker arm.

The operation of the mechanism will be apparent. When the rocker arm swings forward, the face of its upper end engaging the face 20 of the boss 14 moves the driving rod forward in the direction to actuate the let-off mechanism. During this movement the driving rod is supported by the link and all the connections are of a pivotal character. There is a minimum wear due to this pivotal motion and to the character of the engagement between the rocker arm and the boss. The lost motion required when the pawl 4 retracts is readily taken care of because the boss 14 and the upper end of the rocker arm simply separate with the link 16 still supporting the driving rod.

All motion which is transmitted to the driving rod from the rocker arm is transmitted through direct contact of the boss 14 with the arm itself. Since it is only during this contact of the boss 14 with the arm that a substantial force is transmitted, and since none of that force is exerted at the pivot points it follows that the pivots are never subjected to a substantial force.

It will be seen that all the parts are ca-

pable of ready manufacture, are of simple and rugged construction, and are readily replaceable whenever desired.

There is thus provided a very simple and efficient construction for obviating the defects heretofore existing in this mechanism and for securing long life to the parts.

Having thus described the invention, what is claimed as new, and desired to be secured by Letters Patent, is:

1. A let-off mechanism for looms comprising an endwise movable driving rod, a rocker arm for moving the driving rod in one direction, a link pivoted at one end to the rocker arm and at the other end to and supporting the end of the driving rod, and a boss on the driving rod extending opposite the rocker arm and engaged thereby when the rocker arm swings in the direction to move the driving rod.

2. In a let-off mechanism for looms, the construction defined in claim 1, in which the boss on the driving rod is concentric with the pivotal connection of the driving rod with the link.

3. In a let-off mechanism for looms, the construction defined in claim 1, in which the boss on the driving rod is concentric with the pivotal connection of the driving rod with the link, and in which the face of the boss engaging the driving rod is curved to maintain constant the distance between the axis of said pivotal connection and the line of engagement of the boss and rocker arm as the rocker arm rocks in engagement with the boss.

4. In a let-off mechanism for looms, the construction defined in claim 1, in which the link is provided with a pair of parallel laterally extending studs by which it is pivotally mounted in the rocker arm and driving rod respectively, thus enabling the link to be readily removed, together with means for locking the link in connected position.

5. A let-off mechanism for looms comprising an endwise movable driving rod, a rocker arm for moving the driving rod in one direction, a link pivoted at one end to the rocker arm and at its other end to the driving rod to constitute a loss motion connection therebetween, a boss on the driving rod extending opposite the rocker arm and engaged thereby when the rocker arm swings in the direction to move the driving rod, said boss absorbing substantially all the force necessary to move the rod thereby subjecting the pivot points to no substantial force.

6. A let-off mechanism for looms comprising an endwise movable driving rod, a rocker arm for moving the driving rod in one direction, a link pivoted at one end to the rocker arm and at its other end to the driving rod thereby to permit relative movement therebetween, said link with its connection to the driving rod being capable of assembly upon

the rocker arm from either side thereof, and a boss on the driving rod extending opposite the rocker arm and engaged thereby when the rocker arm swings in the direction to move the driving rod.

7. A let-off mechanism for looms comprising an endwise movable driving rod having a transverse bearing in its end, a rocker arm for moving the driving rod in one direction, the said rocker arm having a transverse bearing above its rocking axis, a link having a pair of laterally projecting bearing studs adapted to cooperate with the transverse bearings in the driving rod and in the rocker arm and insertable therein, and means for holding the driving rod, rocker arm and link in assembled position.

8. A let-off mechanism for looms comprising an endwise movable driving rod having a transverse bearing in its end, a rocker arm for moving the driving rod in one direction, the said rocker arm having a transverse bearing above its rocking axis, a link having a pair of laterally projecting bearing studs adapted to cooperate with the transverse bearings in the driving rod and in the rocker arm and insertable therein, and means on one of the studs of the link for holding the driving rod, rocker arm and link in assembled position.

9. A let-off mechanism for looms having the construction defined in claim 7, in which the link is offset between its ends and in which symmetrical bosses are disposed on the rocker arm concentric with and containing the transverse bearing aperture thus to permit the parts to be assembled with the driving rod and the link at either side of the rocker arm.

40 In testimony whereof, I have signed my name to this specification.
